[57] CLAIM

The ornamental design for a bench for physiotherapeutical treatment, as shown.

DESCRIPTION

FIG. 1 is a perspective view of a bench for physiotherapeutical treatment showing my new design;

FIG. 2 is a perspective view thereof, in a raised position;

FIG. 3 is an end elevational view thereof;

FIG. 4 is an end elevational view thereof, opposite that shown in FIG. 3;

FIG. 5 is a side elevational view thereof; and

FIG. 6 is a side elevational view thereof, opposite that shown in FIG. 5.
